UNITED STATES PATENT OFFICE.

WILLIAM ROGERS, OF WALLINGFORD, CONNECTICUT, ASSIGNOR TO SIMPSON
HALL MILLER & CO., OF SAME PLACE.

DESIGN FOR SPOON AND FORK HANDLES.

SPECIFICATION forming part of Design No. 11,745, dated April 20, 1880.

Application filed March 3, 1879. Term of patent 3½ years.

To all whom it may concern:

Be it known that I, WM. ROGERS, of Wallingford, in the county of New Haven and State of Connecticut, have invented a new Design for Spoon and Fork Handles; and I do hereby declare the following, when taken in connection with the accompanying drawing and the letters of reference marked thereon, to be a full, clear, and exact description of the same, and which said drawing constitutes part of this specification, and represents in the figure a face view.

This invention relates to a design for the handles of spoons and forks; and it consists in the configuration and ornamentation, as shown in the accompanying illustration.

About midway of the length of the handle is a boss, *a*. From this point the handle expands, the edges *b* being straight to the end, then turning abruptly inward it curves *c* of about a quarter-circle, the upper termination of said curves being joined by two straight lines, *d*, meeting at an obtuse angle in the center of the end. Following the outlines *b* and *c* is a bead formed of full lines and an internal line made of alternate dots and dashes. This bead does not follow the angular tip formed by the lines *d*, but extends across the tip in an arc of a circle, *e*, from one of the curves *c* to the other. At the end of the handle and within this bead is a panel, *f*, having its upper curve following the curve *e* of the bead, and its sides corresponding with the

shape of the handle, the bottom line of said panel being also curved upward. This panel contains as ornament a central flower with divergent tendrils on a mat ground, and is surrounded by a broad projecting band, *g*, following its contour. About midway of the upper part or section of the handle a curved-upward segmental panel, *h*, is placed, containing a central ornament upon a mat ground, and under said segmental panel *h* is placed a floriated and wavy branch, as shown in the accompanying illustration.

I am aware that it is not new to form a spoon or fork handle with expanding straight sides, as this has been done for at least ten years last past, and do not claim this form, broadly; but

What I claim is—

The herein-described design for spoon and fork handles, consisting of the gradually-expanding straight sides terminating in inward curves *c* and straight lines *d*, meeting at the end, and a bead having its upper line, *e*, curved, with a panel, *f*, having its upper and lower lines segmental and curved upward, said panel having a depressed mat ground and bright relief ornaments, surrounded by a bright band, *g*, all together as shown in the accompanying illustration.

WM. ROGERS.
